(57) **CLAIM**

The ornamental design for screen for vent, as shown and described.

DESCRIPTION

FIG. 1 is a top right perspective view of a screen for vent showing my new design.

FIG. 2 is a front view thereof.

FIG. 3 is a rear view thereof.

FIG. 4 is a top view thereof.

FIG. 5 is a bottom view thereof.

FIG. 6 is a right side view thereof; and,

FIG. 7 is a left side view thereof.

The broken lines in the figures are for the purpose of illustrating portions of the screen for vent and form no part of the claimed design.
